(57) **CLAIM**

The ornamental design for a mirror with arm, as shown and described.

DESCRIPTION

FIG. 1 is a front, right, top perspective view of a mirror with arm showing my design therefor;

FIG. 2 is a rear top left perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

Throughout the drawings, the broken lines indicate environment only and form no part of the design.
